UNITED STATES PATENT OFFICE.

MILTON W. MORSE, OF MOUNT VERNON, NEW YORK.

LAMP-SOCKET.

1,301,152.

Specification of Letters Patent. Patented Apr. 22, 1919.

Application filed August 3, 1916. Serial No. 112,883.

To all whom it may concern:

Be it known that I, MILTON W. MORSE, a citizen of the United States of America, and resident of Mount Vernon, in the county of

5 Westchester and State of New York, have invented certain new and useful Improvements in Lamp-Sockets, of which the following is a specification.

This invention is a lamp socket, and more particularly a lamp socket for use with lamps embodying two filaments, which filaments are generally of different size so that when a current is passed through one of the filaments a bright light results, but when 10 the current is passed through the other filament a relatively dim light is produced. Lamps of this general character have long been in use, the larger or brighter filament being used for reading, etc., while the 15 smaller filament is adapted for use as a nightlight in sleeping rooms, halls and the like where a strong light is not desired.

It has generally been the practice in constructing lamps of this character to vary the 20 intensity of light in filaments of different sizes by the employment of varying resistances and, while such lamps produce the desired degree of light, they manifestly require substantially the same amount of current 25 to operate the smaller filament as when the larger filament is employed. Thus, though much less light is produced when the smaller filament is in incandescent state, substantially the same amount of power is required 30 to furnish this smaller amount of light. In lamps of this character there is, therefore, no saving in the smaller light over the greater light.

With the foregoing in mind, the present 35 invention has for its object the provision of an improved lamp socket wherein no resist- ant means is required and wherein the electric current is fed directly from the supply wire to either of the larger or smaller fila- 40 ments, whereby much less power is required to raise the smaller filament to incandescence then is required to similarly condition the larger filament.

A further object of the invention is to 45 provide an improved construction which is operable by a pull chain connection for placing either of the filaments of the lamp in electrical communication with the source of power and subsequently disconnecting 50 either of said filaments.

Features of the invention, their attain-

ments and advantages, other than those specified, will be apparent from the following description, read in conjunction with the accompanying drawings.

In the accompanying drawings, I have illustrated one practical embodiment of the present invention, but the construction shown therein is to be understood as illustrative, only, and not as defining the limits 60 of the invention.

Figure 1 is a vertical section through a lamp socket embodying the present invention, said section being taken substantially in the plane of line 1—1 of Fig. 2.

Fig. 2 is a similar section taken in the plane of line 2—2 of Fig. 4.

Fig. 3 is a like section taken in the plane of line 3—3 of Fig. 2.

Fig. 4 is a horizontal section taken in the plane of line 4—4 of Fig. 3.

Fig. 5 is a like section taken in the plane of line 5—5 of Fig. 2.

Fig. 6 is a detail elevation of a segmental 70 operating member which I prefer to employ.

Figs. 7 and 8 are an elevation and edge view, respectively, of a clutch member adapted to coöperate with the segmental member of Fig. 6.

Figs. 9 and 10 are an elevation and top 75 plan view of the form of lamp adapted to coöperate with the lamp socket of this invention.

Referring to the drawings, A indicates an outer shell or casing, preferably formed 80 from sheet metal as usual, provided interiorly of its lower portion with the usual helically corrugated shell B into which the plug C of a lamp C' is adapted to be screwed. The upper edge of the inner shell B abuts 85 the lower face of a partition D of insulating material, preferably porcelain fiber or the like, which partition is secured within the outer shell A in any suitable manner.

The top of the shell A is closed by an upper partition E of insulating material, and a covering shell F is adapted to overlie the partition E and close the top of the outer shell, being secured to said shell in any suitable manner.

Interposed between partitions D and E are a pair of oppositely positioned complementary metallic plates g of arcuate cross section, as shown in Fig. 4. These plates seat at their upper and lower edges in arcuate slots g' formed in the partitions D and E, whereby said plates are maintained in

rigid fixed position and free from engagement with the outer shell so as to be insulated therefrom.

The current is fed to the socket through a cable H which is passed through an opening h in the cover F, the positive and negative wires of which cable are secured to two binding post i i'. Binding post i is in the form of a bolt which passes through the upper partition E and extends downwardly through the lower partition D into electrical communication with the inner shell B of the socket. The binding post i' is in the form of a screw, secured in the upper partition and having electrical connection through a wire or plate i² with one of the arcuate plates g as clearly shown in Fig. 2.

Journalized at its opposite ends in the plates g and extending in horizontal position, is a shaft or spindle J on which is loosely mounted a commutator disk K, preferably of conductive material, and provided on its periphery with a plurality of spring contacts k. Commutator K is adapted to be rotated by means hereinafter described, and, during such rotation, the spring contacts k are adapted to be periodically brought into, and subsequently moved out of engagement with fixed contact plates L L'. These plates are curved on a radius concentric with the shaft J and are insulated from one another by the insulating character of the partition D, on upstanding portions of which they are supported. The contact plate L is connected in any suitable way, such as by a wire m, with a contact l positioned on the under side of the partition D and centrally thereof, while the contact plate L' is electrically connected by wire m', or other suitable means, to a brush l' also fixed on the under side of partition D but off center. The relation between the contact l and brush l' is clearly shown in Fig. 5 and these parts are so positioned that when a lamp is screwed into the socket, contact l is adapted to engage with a pin, or other suitable contact, M positioned at the center of the plug of the lamp, while brush l' is adapted to be engaged by a collector ring M' concentric with the pin M and also fixed to the lamp plug, as shown best in Figs. 9 and 10.

As hereinbefore stated, and shown in Fig. 9, the lamp C' is provided with two filaments c and c', the former of which is smaller than the latter. Filament c is connected at one end to the shell of the plug of the lamp, as is usual, and terminates at its other end in the pin M. In like manner the larger filament c' is connected to the shell of the plug and terminates at its other end in an electrical connection with the collector ring M'. Thus, when the lamp is screwed into the socket, the smaller filament c will be placed, through contact l, in com-

munication with the contact plate L, whereas the larger filament c' will be electrically connected, through brush l', with the contact plate L'.

It will thus appear that, if the commutator is rotated to bring one of the spring contacts k into engagement with the contact plate L', a circuit will be completed through a large filament of the lamp, but, if one of said spring contacts is brought into engagement with contact L, the smaller filament will be placed in the circuit. Furthermore, if spring contacts k are not engaged with either of the plates L L' then neither filament will be energized and the lamp will be dead."

Suitable means is provided for imparting rotation to the commutator K to control the current dispensation, but, in the preferred form shown in the drawings, this means is of such character that it may be readily operated by means of a pull chain N which passes through an outlet n in the outside shell and into convenient and accessible position. The end of the chain N is secured on the remote side of a segment O, as at n'. Segment O is mounted for oscillation on shaft J but is normally held in a direction to draw a portion of the chain into the external shell by means of a spring o coiled around shaft J with one end affixed to the adjacent plate g and the other end secured to the segment O. The tension of spring o normally serves to maintain segment O in retracted position, as shown in Fig. 3. The segment O is, moreover, electrically insulated from the shaft J so that an operator, in pulling the chain or cord N, will not receive shocks.

The face of the segment O, adjacent the commutator disk, K, is provided with a plurality of laterally extending shoulders or ratchet teeth j, as shown in Fig. 6, and upon the adjacent face of commutator disk K is secured a similarly formed plate P, shown in Figs. 7 and 8, provided with similar shoulders or ratchet teeth p. For convenience in manufacture, the plate P is made separate and subsequently secured to the segment O although, if desired, the ratchet teeth p may be formed directly upon the segment, this structural difference being immaterial. It will be manifest that in either case, the ratchet teeth p are opposed to the ratchet teeth j and both ratchet teeth are swung on substantially the same radii.

When the parts are assembled in the manner described, the spring o, besides impelling the segment into a retracted position, simultaneously forces the segment O toward the adjacent face of the commutator with the result that the ratchet teeth p and j are maintained in co-operative relation. As the commutator disk K and segment O are mounted on the shaft J for

relative rotation, it will be manifest that the rotation of the segment in a direction opposed to the ratchet teeth of the commutator will cause the commutator to be moved 5 with the segment, and the arrangement is such that this result is accomplished by the pulling of the chain or cord N. Assuming, therefore, that chain N is pulled, it will be obvious that the oscillation of the segment 10 in such direction will impart rotary movement to the commutator and that, as soon as the chain is released, the spring o will return the segment to its retracted position, during which return movement the coöperating ratchet teeth will ride idly over one another so that the commutator is left in the position into which it was moved by the 15 pulling of the chain.

By operating the commutator in the manner described, *i.e.*, by successive operations of the chain, the spring contacts k may be brought into position to energize the larger filament c', the smaller filament c, or it may be moved in such position as to render 25 the lamp "dead."

Spring contacts k are preferably so organized that, when in engagement with either of the contact plates, they are under tension and, as noticeable in Fig. 1, said 30 spring contacts in leaving either of the contact plates are free to quickly assume their retracted positions. It will thus be clear that if a commutator is moved from the position shown in Fig. 1, in a clockwise direction, the spring contact k, which is closing 35 the circuit through the larger filament c, will be moved to the dotted line position between contact plates L L', in which position neither plate will be engaged and the circuit will be broken. However, in assuming 40 the dotted line position, the movement of the spring will be of a sudden nature so that when it slips off the end of the plate L' and engages with the upper face of the partition D, a sharp clicking noise may be heard. This clicking noise will be repeated when, 45 by a successive operation of the commutator, said spring contact leaves the plate L and engages with the upstanding portion d' of the bracket on which plate L is mounted.

Thus, when an operator pulls the pull cord or chain N, the movement of the spring contacts out of engagement with the circuit closing devices to break the circuit, 50 gives an audible signal to the operator that the operation which he was carrying out by pulling the cord is completed and apprises him of the fact that further operation of the chain is unnecessary to complete one step 55 in the cycle of operations.

By the structural arrangements hereinbefore described, the commutator may be rotated to a position shown in Fig. 1, wherein the circuit through the larger filament is 60 completed; by subsequent operation the com-

mutator may be shifted to the dotted line position of Fig. 1, wherein the circuit is broken and the lamp is dead; by a still further operation, the smaller filament may be placed in circuit and by a subsequent operation deenergized. In the structure shown, 70 the cycle of operations consists in, first energizing the larger filament, then rendering the lamp dead, then energizing the smaller filament and, lastly, rendering the lamp 75 dead. These operations are carried out by successive operations of the pull cord or chain N, at the will of the operator.

The foregoing arrangement of the parts is very simple and the resulting structure 80 is highly effective and efficient in its operation, the minimum number of parts and each part operates upon basic mechanical principles. It is impossible to insert a lamp in such manner that its filaments will not be 85 operatively associated with the electrical connections of the socket, and the insulation throughout is so thoroughly carried that danger of electric shocks is absolutely precluded.

It will be understood that slight changes and modifications may be made in the specific structure described without departing from the spirit of the invention, the scope of which is commensurate with the appended 95 claims.

Having thus fully described the invention, what I claim as new, and desire to secure by Letters Patent, is:

1. As a new article of manufacture, a two 100 filament lamp socket embodying a housing shell, partitions of insulating material positioned across the upper and lower portions of the shell, arcuate members positioned in complementary relation between said partitions and one of which members is electrically connected with a source of electrical energy, a shaft mounted at its opposite ends in said members, a commutator device mounted for rotation on said shaft and electrically connected with the current-carrying member, means for intermittently rotating 105 said device, and contacts mounted on the upper face of the lower partition and adapted to coöperate with the commutator device, in 110 combination with means, positioned beneath the lower partition, and supported thereby, for securing a multi-filament lamp in place, contacts on the under side of said lower partition, to be engaged by the corresponding 115 contacts of the lamp associated with the socket, electrical connections between certain of the contacts on the under side of the lower partition and the corresponding contacts on the upper side thereof, and electrical 120 connections between the remainder of the lamp engaging contacts and the source of electrical energy.

2. As a new article of manufacture, a two 125 filament lamp socket embodying a housing 130

shell, partitions of insulating material positioned across the upper and lower portions of the shell, arcuate members positioned in complementary relation between said partitions and one of which members is electrically connected with a source of electrical energy, a shaft mounted at its opposite ends in said members, a commutator mounted for rotary movement on said shaft, electrical connections between the current-carrying member and the commutator, a segment also mounted on the shaft and adapted for rotary movement relative to the commutator, means for normally maintaining the segment in retracted position, a flexible tension member coöperating with said segment and extending to a position exterior of the housing shell for rotating the segment away from its retracted position, ratchet connections between the segment and the commutator for imparting movement to the commutator when tension is applied to the tension member, and contacts mounted on the upper face of the lower partition and adapted to coöperate with the commutator device, in combination with means, positioned beneath the lower partition, and supported thereby, for securing a multi-filament lamp in place, contacts on the under side of said lower partition, to be engaged by the corresponding contacts of the lamp associated with the socket, electrical connections between certain of the contacts on the under side of the lower partition and the corresponding contacts on the upper side thereof, and electrical connections between the remainder of the lamp engaging contacts and the source of electrical energy.

3. As a new article of manufacture, a two

filament lamp socket embodying a housing shell, a partition of insulating material across the interior of said shell, a shaft, a rotary commutator mounted on the shaft and electrically connected with a source of electrical energy, a segment also mounted on the shaft and adapted for rotary movement relative to the commutator, means for normally maintaining the segment in retracted position, a flexible tension member coöperating with said segment and extending to a position exterior of the housing shell for rotating the segment away from its retracted position, ratchet connections between the segment and the commutator for imparting movement to the commutator when tension is applied to the tension member, and contacts mounted on the upper face of the lower partition and adapted to coöperate with the commutator device, in combination with means, positioned beneath the lower partition, and supported thereby, for securing a multi-filament lamp in place, contacts on the under side of said lower partition, to be engaged by the corresponding contacts of the lamp associated with the socket, electrical connections between certain of the contacts on the under side of the lower partition and the corresponding contacts on the upper side thereof, and electrical connections between the remainder of the lamp engaging contacts and the source of electrical energy.

Signed by me at Mount Vernon, N. Y., this 20th day of July, 1916.

MILTON W. MORSE.
